UNITED STATES PATENT OFFICE.

WALTER S. MENDENHALL, OF COVINGTON, KENTUCKY, ASSIGNOR TO
ELEANOR TATUM, (ADMINISTRATRIX OF SAMUEL O. TATUM, DE-
CEASED,) OF CINCINNATI, OHIO.

TELEPHONE-TABLET.

SPECIFICATION forming part of Letters Patent No. 435,314, dated August 26, 1890.

Application filed April 25, 1890. Serial No. 349,490. (No model.)

To all whom it may concern:

Be it known that I, WALTER S. MENDENHALL, a citizen of the United States, and a resident of Covington, in the county of Kenton and State of Kentucky, have invented certain new and useful Improvements in Telephone-Tablets, of which the following is a specification.

The object of my invention is to provide a tablet which can be readily attached or connected to a telephone box, desk, table, or other convenient place, so as to hold the paper in position and furnish a shelf on which to write.

Another object of my invention is to provide a gravity tension for holding the paper taut, the parts being so constructed that it can be readily attached or detached and can be shipped knocked down for the purpose of attachment, all of which will be fully set forth in the description of the accompanying drawings, making a part of this specification, in which—

Figure 1 is a perspective view of my improvement in position for use. Fig. 2 is a bottom plan view of the same. Fig. 3 is a longitudinal vertical section of the roll.

1 represents the lid of a telephone-battery box; 2, the bed of the tablet.

3 represents hooked bars attached to the under side of the bed 2 and preferably made detachable therefrom. The clamps are provided with a slot *a* in the end which passes under the head of screws *b*.

c represents the head of the second screw. One of the clamps is shown slotted at *d*, so that it may be engaged with said screws without taking out the same by simply loosening the screws if it is desired to remove them, and tightening the same when desired to secure them, while the other is shown permanently secured to the bed 2.

4 represents a catch, the shank of which is provided with a slot 5, through which passes the screw 6. This catch engages with the overhanging edge of the lid 1 of the telephone-box and serves as a brace against the lid opposite hooks 8 of the bars 3.

7 represents a paper roll. It is held in position by a shaft or cylinder B, having guides 10, journaled between slotted standards 9. The shaft or cylinder may be composed of solid metal, or it may be hollow and weighted. It may be made of wood and filled with metal or fine gravel or sand, the weight of which will hold the paper down upon the bed of the tablet. The weight is sufficiently heavy to produce the requisite amount of friction to prevent the paper from unwinding too freely, thereby preserving the desired tension for holding the paper in position for writing and to prevent it from pulling out too freely.

11 represents a cutter under which the paper A passes from the roll.

Mode of operation: The hook 8 of the clamps 3 are secured over one edge of the lid 1 of the telephone-battery box. The catch 4 is adjusted to engage under the opposite side of said lid. The screw 6 is turned up, thereby firmly securing the tablet to the box-lid. The paper is drawn forward, passing under knife 11, and is ready for writing. The weight of the shaft is sufficient to prevent the paper from unwinding too freely even when it is nearly wound off, but not great enough to prevent the paper from being pulled off without tearing the same, except when it is raised to come in contact with knife 11.

Having described my invention, what I claim is—

1. A telephone-tablet composed, substantially, of the bed 2, the hook-bars 3, the catch 4, adapted to be secured to the lid of the telephone-box, substantially as specified.

2. In combination with the tablet 2, with device for attaching the same to the lid 1, the weighted roll 7, secured by slotted standards 9 upon the upper side of said tablet, substantially as specified.

In testimony whereof I have hereunto set my hand.

WALTER S. MENDENHALL.
